UNITED STATES PATENT OFFICE.

RUFUS BENZIGER, OF CHICAGO, ILLINOIS, ASSIGNOR TO WARNER SILVER MANUFACTURING COMPANY, OF CHICAGO, ILLINOIS, A CORPORATION OF ILLINOIS.

DESIGN FOR A PICTURE-FRAME.

SPECIFICATION forming part of Design No. 36,256, dated March 31, 1903.

Application filed February 16, 1903. Serial No. 143,584. Term of patent 7 years.

To all whom it may concern:

Be it known that I, RUFUS BENZIGER, a citizen of the United States, residing at Chicago, in the county of Cook and State of Illinois, have invented and produced a new, original, and ornamental Design for Picture-Frames, of which the following is a specification, reference being had to the accompanying drawings, forming part thereof.

Figure 1 is a face view of a picture-frame, showing my new design. Fig. 2 is a view, partly in section and partly in elevation, taken on line xx , and Fig. 3 is a similar view taken on line yy , of Fig. 1, the arrows indicating the direction in which the views are taken in both Figs. 2 and 3.

As shown in the drawings, the leading or material feature of my design consists of a circular piece or ring A, having its front or face surface plain and bordered with an open-work leaf-like ornamentation. The front or face portion of the ring or piece A is slightly curved, as at a , and has extending rearwardly therefrom a straight portion b , as is clearly shown in Figs. 2 and 3 of the drawings. The open-work ornamentation consists of a series of curved portions c and c' , connected to the

outer surface of the piece A and arranged so that they will present their open portions alternately from the piece A or ring. Each of these circular portions is formed with indentations d on its front surface to produce a leaf-stem-like effect and have extending one from the other and connecting them together on their front surfaces branches C, which terminate in leaf-like portions D, which project forwardly and are slightly drooping, as shown. The upper portion of the border on the ring or piece A has extending upwardly two branches e , which terminate in enlarged leaf-like portions D' , which project forwardly and are also slightly drooping.

Having described my invention, what I claim as new, and desire to secure by Letters Patent, is—

The ornamental design for a picture-frame, substantially as shown and described.

In testimony whereof I have hereunto signed my name to this application in the presence of two subscribing witnesses.

RUFUS BENZIGER.
